UNITED STATES PATENT OFFICE.

WASHINGTON HARRIS, OF PHILADELPHIA, PENNSYLVANIA.

IMPROVEMENT IN NON-CONDUCTING COVERING FOR BOILERS, STEAM-PIPES, &c.

Specification forming part of Letters Patent No. 98,865, dated January 12, 1870.

I, WASHINGTON HARRIS, of the city of Philadelphia, in the State of Pennsylvania, have invented certain Improvements in the Mode of Applying Heat-Retaining or Non-Conducting Coverings to Steam Pipes, Drums, Generators, &c., of which the following is a specification:

Nature and Objects of the Invention.

My invention relates to the construction and application of a series of curved covering shells or tiles, molded either of brick-clay or of plaster-of-paris, or plaster-of-paris and lime, or plaster-of-paris and ashes, or any other suitable poor conductor of heat, in such a manner that the said series can be readily applied and secured around the pipes or drums, or upon steam-generators, &c., so as to afford a covering of shells or tiles, either with or without an air-space confined between the said covering-shells and the steam-vessel, the object of my invention being to facilitate in covering and also in uncovering the pipes, drums, or generators without destroying the said covering for reapplication, and in producing a more effective and reliable preventive of the loss of heat by radiation from the said heat-containing vessels.

Description of the Accompanying Drawings.

Figure 1 is a central longitudinal section of a steam-pipe and of the halves of two of the shells or tiles applied thereto at its mid-length, with a view of the inner sides of two like shells or tiles in connection with the pipe, and with the sections of shells on the middle of the same. Figs. 2 and 3 are views of the two ends of a pair of the said shells or tiles as applied together around the steam-pipe, the dotted lines thereon indicating the lines of junction, respectively, of the next adjoining pair of tiles.

General Description.

All the shells or tiles A of the series are made in a mold in the form of the longitudinal half of a hollow cylinder, with a groove, b, along in one edge, and a corresponding tongue, e, along in the opposite edge, and a groove, d, in one end, and a corresponding tongue, e, on its opposite end, and also a bearing-rib, f, around on the inner side of the grooved end, which fits around against the pipe G.

The shells or tiles are applied around a

steam pipe or drum in the following manner, viz: Commencing at one end, two of the shells A are closed together around the same, with a little cement of plaster-of-paris or any other suitable cement in each groove b, and secured together by a wire wound two or three times around the outer end and secured thereat, and then the next pair of shells, with cement in both grooves b and d, applied around the pipe and slipped along, so as to bring the end tongues, e e, of one pair into the end grooves, d d, of the other pair, and with the plane of the two side joints of the last-applied pair at right angles to the plane of the two side joints of the immediately preceding pair, and so on in succession until the whole pipe or drum is covered, and then securing the last one by winding wire two or three times around it and fastening it thereat; and finally closing up the two ends of the series with the cement, or with a suitable cap and cement, the intervening shells being sufficiently held by their tongues and grooves alone.

It will be understood without further description that by means of these shells or tiles, applied as described, an air-chamber, h, will be left between each section of the series of the hollow cylinders and the heated vessel which it surrounds, which air-space in connection with the said covering-shells of poor heat-conducting material form together the best non-conducting covering that has as yet been applied, and that, while the said shells can be applied securely and with facility, they can be removed and reapplied at any time, without breaking or injuring them, whenever a leak in the steam pipe or drum requires to be stopped or a new one to be substituted.

Claim.

I claim as my invention—

The shells or tiles A A, constructed and applied to steam pipes, drums, or other heated vessels, so as to produce a non-conducting covering, either with or without the confined air-space between the said shells and the vessel covered thereby, substantially as and for the purpose hereinbefore set forth.

WASHINGTON HARRIS.
